(57) **CLAIM**

I claim the ornamental design for a putter grip, as shown.

DESCRIPTION

FIG. 1 is a perspective view from the front, left side, and top of a putter grip showing my new design;

FIG. 2 is a front elevational view thereof;

FIG. 3 is a rear elevational view thereof, being identical to FIG. 2;

FIG. 4 is a left side elevational view thereof;

FIG. 5 is a right side elevational view thereof, being a mirror image of FIG. 4;

FIG. 6 is a top plan view thereof;

FIG. 7 is a bottom plan view thereof; and,

FIG. 8 is a perspective reference view of a putter grip showing my new design in which the broken line shows environmental structure that forms no part of the design to be patented.
